DROP-LEAF DINING TABLE

Rennold J. Luger, Minneapolis, Minn., assignor to Luger Furniture Company, Minneapolis,
Minn., a corporation of Delaware

Application May 27, 1953, Serial No. 25,206

Term of patent 14 years

(Cl. D33—14)

To all whom it may concern:

Be it known, that I, Rennold J. Luger, a citizen of the United States of America, residing at 3207 Fremont Avenue South, Minneapolis, county of Hennepin, State of Minnesota, whose post-office address is 3207 Fremont Avenue South, Minneapolis, Minnesota, have invented a new, original, and ornamental Design for Drop-Leaf Dining Table, of which the following is a specification, reference being made to the accompanying drawings forming a part thereof, and in which:

Fig. 1 is an end elevational view of a drop leaf dining table showing my new design, the leaves being shown in dropped position;

Fig. 2 is an end elevational view thereof, the leaves being extended;

Fig. 3 is a side elevational view thereof in dropped position;

Fig. 4 is a similar view thereof in extended position;

Fig. 5 is a top plan view thereof in extended position; and

Fig. 6 is a top plan view thereof in dropped position.

I claim:

The ornamental design for a drop-leaf dining table, substantially as shown.

RENNOLD J. LUGER.
